UNITED STATES PATENT OFFICE.

JOSEPH F. CURRY, OF NEWARK, NEW JERSEY, ASSIGNEE TO ULYSSES G. CLARK, OF NEW YORK, N. Y.

LOCK-JOINT FOR WIND-SHIELDS.

1,074,639.

Specification of Letters Patent.

Patented Oct. 7, 1913.

Application filed April 10, 1913. Serial No. 760,231.

To all whom it may concern:

Be it known that I, JOSEPH F. CURRY, a citizen of the United States, residing at Newark, in the county of Essex and State of New Jersey, have invented a new and useful Improvement in Lock-Joints for Wind-Shields; and I do hereby declare the following, when taken in connection with the accompanying drawings and the characters of reference marked thereon, to be a full, clear, and exact description of the same, and which said drawings constitute part of this application, and represent, in

Figure 1 a side view of a lock-joint constructed in accordance with my invention. Fig. 2 a transverse sectional view of the same. Fig. 3 a perspective view of the locking-wedge detached. Fig. 4 a sectional view illustrating a modified form of wedge.

This invention relates to an improvement in lock-joints for wind-shields, the object being to provide a firm lock for the joint which permits of ready adjustment, and the invention consists in the construction hereinafter described and particularly recited in the claims.

In carrying out my invention I employ a socket 2 having a centrally arranged circular chamber 3, the socket being provided with the usual stump 4 for attachment to the body of an automobile. At one side of the socket 2 is an offset sleeve 5 formed with a cam-shaped recess 6 to receive a wedge 7 which is adapted to be crowded into the recess by a screw 8 provided with a finger-piece 9.

Attached to the frame 10 of the wind-shield is a circular hub 11 fitting the chamber 3 and adapted to freely turn therein. The wedge 7 which bears against the hub comprises two reversely turned arms 12 and 13 which, as shown in Fig. 2 of the drawings, are made integral with the wedge and formed by cutting an inwardly extending slot 14 opening into a transverse hole 15

which will allow of sufficient movement of the arms 12 and 13. It is apparent, however, and as shown in Fig. 4 of the drawings, that arms 16 and 17 may be formed separate from the plug 18 and pivoted thereto, the result being substantially the same, namely, that the inward movement of the plug crowds the arms against the hub and locks it against rotation.

With this construction but a slight movement of the screw, and in some cases less than half a turn will be sufficient to so crowd the arms against the hub as to firmly lock it against movement. A similar extent of the movement of the screw in the reverse direction will release it.

I claim:

1. A lock joint comprising a socket formed with a circular chamber and an offset sleeve, a cam-shaped recess between the chamber and sleeve and opening into said sleeve, a hub located in said chamber, a wedge located in said recess, said wedge having arms adapted to be crowded between the walls of said cam-shaped recess and the side of said hub, and means for moving said wedge.

2. A lock joint comprising a socket formed with a circular chamber, an offset sleeve and a cam-shaped recess between said chamber and sleeve and opening into said sleeve, a hub located in said chamber, a wedge located in said recess, said wedge formed with integral reversely turned arms adapted to impinge between the walls of the said chamber and against the said hub, and a screw entering the said sleeve and adapted to crowd the said wedge inward.

In testimony whereof, I have signed this specification in the presence of two subscribing witnesses.

JOSEPH F. CURRY.
